LAMP BASE OR SIMILAR ARTICLE

Donald W. Hansen, New York, N.Y., assignor to Donald Hansen Lamps, New York, N.Y., a partnership

Filed Mar. 8, 1961, Ser. No. 64,192

Term of patent 3½ years

(Cl. D48—20)

FIG. 2 is a top plan view thereof with the socket and shade support omitted for convenience of illustration;

FIG. 3 is a bottom plan view thereof; and

FIG. 4 is a perspective view thereof as seen from the opposite side of FIG. 1 with the socket and shade support omitted for convenience of illustration.

The dominant features of my design reside in the portions shown in full lines.

I claim:

The ornamental design for a lamp base or similar article, as shown and described.
